UNITED STATES PATENT OFFICE.

WILLIS W. DANLEY, OF CHICAGO, ILLINOIS, ASSIGNOR TO THE BOSTEDO
PACKAGE AND CASH CARRIER COMPANY, OF SAME PLACE.

TERMINAL FOR PNEUMATIC-DESPATCH TUBES.

SPECIFICATION forming part of Letters Patent No. 623,520, dated April 25, 1899.

Application filed February 21, 1898. Serial No. 671,047. (No model.)

To all whom it may concern:

Be it known that I, WILLIS W. DANLEY, of Chicago, in the county of Cook and State of Illinois, have invented certain new and useful Improvements in Terminals for Pneumatic-Despatch Tubes, of which the following is a specification.

This invention relates to improvements in terminals for pneumatic-despatch-tube systems, and has for its object to provide a construction adapted for use as a delivery-terminal for the main line or branches of such a system.

The present invention is in the nature of
15 an improvement upon the construction set
forth in an application filed May 17, 1897,
Serial No. 636,976, by Louis G. Bostedo for
"improvements in pneumatic-despatch-tube
systems;" and it consists in certain novel fea-
20 tures, which I will now proceed to describe
and will then particularly point out in the
claims.

In the accompanying drawings, Figure 1 is a central vertical sectional view, partly in elevation, of a pneumatic-despatch-tube terminal embodying my invention, the same being shown in the normal or closed position. Fig. 2 is a similar view, the parts being shown in the position which they assume when the carrier is being discharged from the terminal. Fig. 3 is a side elevation, on an enlarged scale, of that portion of the terminal immediately adjacent to the discharge end thereof. Fig. 4 is a plan view of the same. Fig. 5 is a view similar to Fig. 3, showing a modified form of construction, the parts being in the normal or closed position; and Fig. 6 is a similar view showing the parts in the discharge position.

Referring first to the construction shown in Figs. 1 to 4, 7 represents the terminal portion of the main tube, which is provided near the open discharge end thereof with a gate or valve 8, preferably rectangular in form and mounted in a suitable air-tight casing 9. The valve or gate 8 is pivoted or hinged at the upper side of the main tube, it being provided with an axis or shaft 10, mounted in suitable bearings in the casing 9 at this point. To this axis there is connected a piston 11, the construction being preferably such that the valve or gate 8 and piston 11 form two

similar members arranged at right angles to each other and constructed in one piece with the shaft or axis 10. The casing 9 is semi-cylindrical in shape, the lower portion thereof forming a part of the passage-way of the tube 7, while the piston 11 fits snugly within the upper portion of said casing. The gate or valve 8 and the piston 11 are connected by a curved diaphragm or plate 12, the curvature thereof having the axis 10 as a center, and there is thus formed between the members 8, 11, and 12 an air-chamber 13, which communicates with the interior of the casing 9 by means of a port 14 in the diaphragm 12. 65

15 indicates a fixed diaphragm extending horizontally across the interior of the casing 9 within the air-chamber 13, its edges bearing, respectively, against the shaft 10 and curved plate or diaphragm 12 and being provided, if deemed desirable, with suitable packings, as indicated in Fig. 1, to prevent leakage at its edges. 70

16 indicates a pipe or passage communicating with the air-chamber 13 at a point immediately below the fixed diaphragm 15 and extending thence to a point where it communicates with the interior of the casing 9 or some other part of the system, said pipe or passage being provided with a check-valve 17, 75 which permits free passage of the air toward the air-chamber 13, but prevents its escape from said chamber. 18 indicates a pipe also leading from a point in the chamber 13 immediately below the fixed diaphragm 15 to a 85 connection with the interior of the casing or other suitable part of the system and provided with a regulating-valve 19, whereby the passage may be so reduced as to permit the air to pass only very slowly through said 90 pipe or passage 18, the valve permitting the regulation of the size of the passage to adapt the same to the requirements of the apparatus.

The pipe 18 and valve 19 are broken away in Fig. 4 of the drawings in order to show the construction of the underlying parts.

A pipe 20, similar to the pipe 16 and provided with a check-valve 21, leads from a point in the air-chamber 13 immediately above the fixed diaphragm 15 to a connection 100 with the interior of the casing 9, as shown in dotted lines in Fig. 3, and a pipe 22, provided

with a reducing-valve 23 and corresponding in construction to the pipe 18 and valve 19, also leads from a point in the chamber 13 immediately above the fixed diaphragm 15 to 5 a connection with the interior of the casing 9.

24 indicates a suitable packing bearing against the shaft 10 and adjustable by means of a set-screw or set-screws 25 to make an air-tight joint at this point.

10 At a suitable distance farther from the discharge end of the tube 7 than the location of the valve or gate 8 there is located a second valve or gate 8^a, mounted in a casing 9^a by means of a shaft or axis 10^a and connected 15 with an oscillating piston 11^a. This gate in its construction and details is identical with the valve or gate 8 just described, with the exception that its axis is located below instead of above the main tube 7, so that while 20 the gate 8 is normally closed by gravity the gate 8^a is normally opened by the same force, the normal position of the two being that shown in Fig. 1 of the drawings.

26 indicates a pipe leading from a point in 25 the main tube 7 or casing 9 immediately adjacent to but inside of the gate 8 to a connection with the casing 9^a back of the piston 11^a therein.

27 indicates a pipe extending from a point 30 in the main tube 7 adjacent to the gate 8^a, but between the same and the gate 8, to a connection with the casing 9 back of the piston 11 therein.

28 indicates a by-pass pipe extending from 35 a point in the main tube 7 lying inwardly beyond the valve or gate 8^a to a connection with the pipe 27, and in this pipe 28 is located a valve 29, which is connected to a piston 30 in a cylinder 31. The cylinder 31 is connected 40 with the pipe 28 on one side of its piston by means of a pipe 32, which connects with the pipe 28 at a point between the valve 29 and the connection of the pipe 28 with the main tube 7. On the other side of its piston the 45 cylinder 31 is connected with the main tube 7 or casing 9 at a point adjacent to but inside of the gate or valve 8 by means of a pipe 33.

34 indicates a rod connected to the piston 30 and provided with a notch 35, said rod 50 passing through a locking-rod 36, which is apertured at 37 to receive the same. The locking-rod 36 is mounted to slide vertically in a suitable bracket 38 and is forced normally upward by means of a spring 39, its upper end lying in the path of an arm 40, secured to the shaft or axis 10 of the gate 8.

I may provide in the pipe 26 a check-valve 41, the stem 42 of which is in line with and normally abuts against the end of the rod 34, 60 which holds said valve normally open, a spring 43 serving to close said valve when the rod 34 is withdrawn from contact with its stem.

65 The apparatus thus constructed operates in the following manner: A carrier approaching the terminal in the direction indicated by the arrow in Fig. 1 compresses the air between

itself and the gate 8, and thereby causes the air to pass through the pipe 26 and, operating upon piston 11^a, closes the gate 8^a. At the same time the air thus compressed passes through the pipe 33 to the cylinder 31, and since the pressure thus introduced into the cylinder on one side of the piston 30 thereof is greater than the normal pressure of the system existing on the other side thereof said piston will be so moved as to close the valve 29. After the gate or valve 8^a and valve 29 are closed the advance of the carrier in the tube 7 creates a vacuum or partial vacuum in its rear, which exhausts the air in the pipe 27 and casing 9, thereby moving the piston 11 upward and opening the gate 8. At the same time the movement of the piston 30 has carried the rod 34 over into such a position that the notch 35 thereof will be engaged by the locking-rod 36, which is permitted to move upward under the influence of its spring 39 as soon as the upward movement of the gate 8 has removed the pressure of the arm 40 on the upper end of said rod. The valve 29 is thus locked in a closed position, this locking of the valve being necessary, because otherwise when the gate 8 is opened the pressure on that side of the piston 30 connected with the casing 9 would be reduced to atmospheric pressure and the system pressure through the pipe 32 would reopen the valve 29 if some locking means were not provided. The movement of the rod 34 just described frees the 100 stem 42 of the valve 41, and the same is closed by its spring 43 and prevents the escape of the air in the casing 9^a through the pipe 26 and the consequent opening by gravity of the gate 8^a. The parts are now in the position 105 shown in Fig. 2 and the carrier is discharged from the tube 7. As soon as the carrier clears the tube the pressure on the opposite sides of the piston 11 is equalized and the gate 8 closes by gravity. This movement causes the arm 110 40 to strike the locking-rod 36 and moving the same downward disengages it from the rod 34, whereupon the system pressure on the piston 30 in the cylinder 31 returns the same to the position shown in Fig. 1, thereby opening the 115 valve 29 and also the valve 41. Upon the opening of the valve 29 the system pressure passes through the pipes 28 and 27 to that portion of the main tube 7 on the outer side of the gate 8^a, and the pressure being thus 120 equalized on the opposite sides of said gate it opens by gravity and returns to the position shown in Fig. 1. The parts are now all in their original position ready for the receipt 125 and discharge of another carrier.

Provision is made for cushioning the action of the gates or valves 8 and 8^a and their pistons 11 and 11^a by reason of the construction hereinbefore described. For instance, when the gate or valve 8 begins to open air 130 may pass freely through the pipe 20 and check-valve 21 from the interior of the casing 9 to the interior of the air-chamber 13 between the piston 11 and the fixed diaphragm

15, thereby permitting the said piston to rise and move away from the diaphragm without creating a vacuum between the two parts during the initial portion of its upward movement. As soon as the upper edge of the port 14 has passed clear of the fixed diaphragm 15 the pressure is equalized between the interior of the casing and the air-chamber 13 and the piston and gate continue to move freely upward. At the end of the upward movement of the parts, when the lower edge of the port 14 has passed clear of the fixed diaphragm 15, the air in the chamber 13, between said fixed diaphragm and the gate 8, is compressed as the gate advances. This is due to the fact that the check-valve 17 in the pipe 16 prevents the escape of air through said pipe, while the reducing-valve 19 in the pipe 18 permits only a slow escape of the air inclosed between these parts. The closing portion of the upward movement of the piston and gate is thus cushioned, and shock or pounding of the parts is thus prevented. Upon downward movement of the parts air is freely admitted through the pipe 16 and check-valve 17, so that no vacuum exists within the air-chamber 13 to prevent free movement of the parts. At the end of the downward movement of the parts, after the port 14 has again passed clear of the fixed diaphragm 15, the air is compressed between the piston 11 and said fixed diaphragm, being prevented from passing out through the pipe 20 by the check-valve 21 therein and escaping slowly through the pipe 22 and reducing-valve 23. The gate 8^a and piston 11^a are similarly cushioned by a construction identical with that just described.

The construction of the piston and valve in the manner set forth, being set at an angle to each other on a common axis, is a construction having the advantages of great simplicity and direct connection, dispensing with intermediate connecting devices or parts and adapting the structure to be made with the piston, gate, and shaft in a single piece, which construction I prefer, although it is obvious that the parts may be separately secured to the shaft. The location of the two parts at substantially a right angle to each other is also advantageous in that the parts are not on a dead-center when closed or opened and at a right angle or parallel to the axis of the main tube, but will resume their normal positions by gravity as soon as permitted to do so by the equalization of the pressure.

The apparatus hereinbefore described may be obviously modified as to various details of construction without departing from the principle of my invention. For instance, I have shown in Figs. 5 and 6 a construction in which the rod 34 is operated from the shaft 10 by a slightly-modified mechanism. In this construction the locking-rod 36 rests at its lower end upon the rod 34 by reason of its gravity, and the rod 34 is provided with a projection 35^a, having that side thereof ad-

jacent to the cylinder 31 inclined, while the side farthest from said cylinder forms a vertical shoulder. The upper end of the rod 36 is provided with a lateral projection 36^a, which lies in the path of the arm 40, which in this construction is provided with a hinged extension 40^a, adapted to yield in one direction only and held in place by a spring 40^b. In this construction when the rod 34 passes under the end of the locking-rod 36 the inclined portion of the projection 35^a raises said locking-rod, which subsequently seats itself behind the vertical shoulder of said projection, as shown in Fig. 6, and thereby holds the valve 29 locked. Upon the upward movement of the gate or valve 8 the extremity 40^a of the arm 40 yields upon contact with the projection 36^a, so as to allow said arm to pass said projection and assume the position shown in Fig. 6. Upon the downward movement of the gate 8 the extension 40^a of the arm 40 engages the projection 36^a and lifts the rod 36, thereby freeing the rod 34 and permitting the valve 29 to be opened. In these figures I have also shown the check-valve 41 in the pipe 26 as omitted, as I do not deem its employment essential, although perhaps desirable under certain circumstances. Other modifications will readily suggest themselves, and I therefore do not wish to be understood as limiting myself to the precise details of construction hereinbefore set forth and shown in the drawings.

100 I claim—

1. In a pneumatic-despatch-tube system, a terminal comprising a main tube, two gates or valves located at separated points therein, motors for actuating said gates or valves, a pipe or passage connecting the motor of the inner gate or valve with the main tube at a point adjacent to the outer gate or valve, a valve located in said pipe, and means for closing said valve when the outer gate or valve is open, substantially as described.

2. In a pneumatic-despatch-tube system, the main despatch-tube in combination with two gates or valves located one at the discharge end of the tube and normally closed, and the second some distance inward therefrom and normally open, a motor for the inner gate having a pipe or passage connected with the main tube near the outer gate, a motor for the outer gate having a pipe or passage connected with the main tube on the discharge side of the inner gate, a by-pass connecting the main tube at a point inside of the inner gate with the pipe or passage of the outer gate, and a valve in said by-pass actuated by the variations in pressure caused by the movement of the carrier in the main tube, substantially as described.

3. In a pneumatic-despatch-tube system, a semicylindric valve-casing and a valve and piston fitting therein and mounted at right angles to each other on a common axis, one half of the casing serving as a pressure-chamber for the piston and the other half consti-

tuting a portion of the despatch-tube, substantially as described.

4. The combination, with the main tube, of a casing, a gate, and an actuating-piston therefor mounted to oscillate on a common axis, a curved connecting-plate or diaphragm provided with a port and forming an air-chamber, and a fixed diaphragm within said air-chamber whereby the movement of the gate and piston is cushioned at its limits of motion, substantially as described.

5. The combination, with the main tube and a suitable casing, of a gate or valve, and a piston therefor connected to a common axis,

a curved plate or diaphragm connecting the two and provided with a port and forming an air-chamber, a fixed diaphragm within said air-chamber, and pipes arranged in pairs on opposite sides of said fixed diaphragm, connecting the air-chamber with the casing, and provided respectively with a check-valve and a reducing-valve or contracted portion, substantially as described.

WILLIS W. DANLEY.
